J. W. DODD

ELECTRICALLY RELEASED BRAKE

Filed June 3, 1925

Patented Oct. 23, 1928.

1,688,379

UNITED STATES PATENT OFFICE.

JOHN W. DODD, OF BROOKLINE, MASSACHUSETTS, ASSIGNOR TO GEORGE T. McLAUGHLIN COMPANY, OF BOSTON, MASSACHUSETTS, A CORPORATION OF RHODE ISLAND.

ELECTRICALLY-RELEASED BRAKE.

Application filed June 3, 1925. Serial No. 34,522.

This invention relates to spring applied electrically released brakes of that type particularly suitable for use with electric hoisting or elevator motors, the brake being applied automatically as long as the current is off and the release devices being energized whenever the motor circuit is closed to operate the motor.

One feature of the present invention relates to mechanism by which the release devices act with multiplied force to release the brake against the pressure of the applying springs.

A further feature which may be employed relates to the balancing of the braking and relieving pressure axially of the motor shafts.

Further features and advantageous details and combinations of parts will appear from a more complete description of certain embodiments thereof disclosed in the accompanying drawings in which

Figure 1 is a fragmentary side elevation partly broken away and in section of a motor with one form of brake embodying this invention.

Figures 2, 3 and 4 are detail sections on lines 2-2, 3-3 and 4-4, respectively, of Figure 1.

Figure 5 is a view similar to Figure 1, but
30 showing a modified construction.

Figure 6 is a fragmentary top plan of the same construction.

Figure 7 is a detail section on line 7-7 of Figure 6.

35 Referring first to the embodiment shown in Figure 1, it is believed that

in Figures 1 to 4 inclusive, 1 indicates a portion of the frame or casing of a motor, 2 representing the rotor shaft of the motor on the end of which is carried a braking disk.

40 3. To the motor casing 1 is fixed, as by means of bolts 5, a frame 6. This frame has outwardly extending arms 7 to which are fixed electromagnets 8, these electromagnets as shown having laminated pole pieces 9 sur-

45 rounded by solenoids 10. Adjacent to the rotor shaft 2 the frame 6 is provided with fulcrum posts 11 at the free ends of which are pivotally mounted, as at 12, arms 13. The outer ends of these arms are formed

50 The outer ends of these arms are rounded as at 14 and carry pivoted thereon the laminated armatures 15 for the electromagnets 8. Beneath the disk 3 is a frictional plate 20 having a frictional facing 4 which is movable axially of the rotor

shaft and which is pressed upwardly in contact with the friction material 4 and toward the disk 3 by means of springs 21 bearing over centering posts 22 on its under face and extending over posts 23 having abutment washers 24 thereon held in vertically adjusted position by means of adjusting and lock nuts 25 and 26. The arms 13 pass between pairs of downwardly extending lugs 30 carried by the plate 20 and bear against pins 31 extending between these lugs 30 adjacent to their lower ends. The arms 13 also pass through slotted lugs 35 depending from the plate 20 and in substantial alignment with stop posts 36 extending upwardly from the frame 6. The posts 36 are formed with spaced upstanding portions 37 between which the lugs 35 extend, this or equivalent construction acting to prevent rotation of the plate 20 with the disk 3. It will be noted that the arms 13 bear over the pins 31 close to the fulcrum points 12 of these arms and that the armatures 15 are placed at the free ends of these arms. When the power devices comprising the electro-

the power devices comprising the electromagnets are energized, therefore, and the armatures are brought toward the pole pieces 9, the arms 13 act with an increased leverage against the pins 31 and pull the plate 20 away from the disk 3 against the pressure exerted by the springs 11, thus releasing the brake with a multiplied force over that exerted by the direct attraction of the armatures to the pole pieces. The armatures being mounted for rocking movement on the arms 14 are allowed to adjust themselves angularly to the pull of the electromagnets without imparting torsional stresses to the arms 13. While the frictional material 4 has been described as fixed to the plate 20, of course, if desired, it could be fixed to the disk 3, or of course, it could be fixed to neither, relying on the frictional drag between its opposite faces and the disk and plate, though it is preferred to fix it to the plate as hereinbefore described.

If desired a pair of non-rotating plates may be employed acting against opposite sides of the disk, such a construction being illustrated in Figures 4 to 6. Referring to these figures, the disk 40 having a hub 41 is fixed to the rotor shaft 42 as by means of a pin 43 passing through the hub and shaft. Between the disk 40 and the motor casing 44

is a plate 45 having a hub portion 46 perforated for the reception of pins 47 projecting from the end of the motor casing, the plate 45 being permitted a limited motion axially of these pins, but the pins preventing rotation of the plate 45 relative to the motor casing. The plate 45 is extended at spaced points beyond the periphery of the disk 40 as at 50 and through the portions 50 are passed rods 51, the lower end of each rod being threaded for securement to the plate 45 and for the reception of a nut 52. The upper portion of each of these rods is threaded for the reception of a nut 53 against which 15 bears a washer 54 forming an abutment for one end of a coil spring 55. This spring bears at its opposite end on the outer upper face of an extension 56 of a plate 57 which is positioned above the disk 40 and is permitted movement axially of the shaft 42, but 20 is prevented from rotation by the pins 51 which connect it to the plate 45. On opposite faces of the disk 40 may be positioned disks 60 of frictional material. The upper 25 plate 57 has fixed thereto the electromagnetic releasing devices, such devices, as shown, comprising the laminated cores 65 about which are placed solenoid coils 66. The armature 67 for each of the magnetic devices 30 is carried by a bifurcated arm 70 having its outer end formed as an elongated sleeve 71 35 rockingly supported on a shaft 72 extending between pairs of brackets 73 fixed to or integral with the upper plate 57. These arms 40 adjacent to their fulcrum shaft 71 extend over the upper ends of the threaded pins 51 so that when these electromagnetic devices are energized and the armature drawn toward the pole pieces, pressure is 45 exerted on the pins 51 against the pressure of the springs 55 separating the plates 57 and 45, thus releasing the disk 40 from frictional engagement therewith through the friction disks 60. To limit the upward 50 swing of the arms 70, stop bolts, such as are shown at 75, extend between the forked portions of these arms and are threaded at their lower ends into the plates 57, lock nuts 76 being employed to hold them in adjusted 55 positions. The heads 77 of these bolts 75 are so positioned that the arms 70 engage them if swung upwardly to a sufficient extent. It will be noted that in this construction the arms 70 engage the pins 51 closer to their fulcrums than the armatures 67 are positioned, and hence act with multiplied 60 force to separate the plates 45 and 57 against the pressure exerted by the brake applying springs 55 when the electromagnetic power devices are energized.

Having this described certain embodiments of this invention it should be evident to those skilled in the art that various changes and modifications might be made

therein without departing from its spirit or scope as defined by the appended claims.

I claim:

1. In combination with a rotary shaft, of a disk fixed to said shaft, a plate on each side of said disk movable toward and from said disk but held from rotation therewith, a spring for pressing said plates toward each other to clamp said disk therebetween, and means for forcing said plates apart against the action of said spring to release said disk. 75

2. In combination with a rotary shaft having a disk fixed thereto, of a plate on each side of said disk movable toward and from said disk but held against rotation therewith, springs for forcing said plates toward each other to clamp said disk therebetween, levers actuatable to force said plates away from each other to free said disk, and electromagnetic devices for actuating said levers. 80

3. In combination with a motor having a casing and a rotor shaft, of a disk fixed to rotate with said shaft, a pair of plates, one positioned on each side of said disk and relatively movable axially of said shaft toward and from said disk, means carried by said motor casing for holding the adjacent plate from rotation with said shaft, means projecting from said adjacent plate for holding the other of said plates against rotation, springs for forcing said plates relatively toward each other to clamp said disks therebetween, levers fulcrumed on one of said plates and in operative engagement with the other of said plates, and electromagnetic devices carried by said one plate and when energized acting on said levers in a direction to force said plates apart to free said disk. 90

4. In combination with a rotary shaft, of a disk fixed to said shaft, a plate on each side of said disk relatively movable axially of said shaft to clamp and release said disk therebetween, means for holding one of said plates against rotation, pins extending from said plate through the other of said plates beyond the periphery of said disk, springs surrounding said pins and bearing between abutments thereon and said other plate and acting to press said plates toward each other, electromagnetic devices carried by said other plate, and levers pivoted to said plate and having armatures for said devices, said levers bearing on the said pins and moved by the energization of said devices to force said plates apart to release said disks. 100

5. In combination with a rotary shaft, of a disk fixed to said shaft, a plate on each side of said disk relatively movable axially of said shaft to clamp and release said disk therebetween, means for holding one of said plates against rotation, pins extending from said plate through the other of said plates

beyond the periphery of said disk, springs surrounding said pins and bearing between abutments thereon and said other plate and acting to press said plates toward each other, 5 electromagnetic devices carried by said other plate, levers pivoted to said plate and having armatures for said devices, said levers bearing on the said pins and removed by the en-

ergization of said devices to force said plates apart to release said disks, and means for limiting the swing of said levers in the opposite direction. ¹⁰

In testimony whereof I have affixed my signature.

JOHN W. DODD.
